UNITED STATES PATENT OFFICE.

WILLIAM FRANCIS GIBBS, OF PHILADELPHIA, PENNSYLVANIA.

GASOLENE FIRE-ENGINE.

No. 918,140.

Specification of Letters Patent. Patented April 13, 1909.

Application filed February 5, 1908. Serial No. 414,313.

To all whom it may concern:

Be it known that I, WILLIAM FRANCIS GIBBS, a citizen of the United States, residing at Philadelphia, in the county of Philadelphia and State of Pennsylvania, have invented certain new and useful Improvements in Gasolene Fire-Engines, of which the following is a specification.

My invention relates to improvements in fire engines and particularly to those engines in which gasoline is used as the motive power for operating the pumps.

The object of my invention is to provide a light, strong and durable fire engine of high efficiency and power and such as can be instantaneously started.

A further object of my invention is to construct a fire engine having a gas engine provided with a plurality of single or double acting cylinders.

A still further object of my invention is to so arrange the parts that the main driving-shaft will extend longitudinally with the fire engine.

A still further object of my invention is to provide one or more rotary pumps, driven by direct gearing from the main driving-shaft.

A still further object of my invention is to provide a single frame for the engines and pumps.

A still further object of my invention is to provide a water-jacket to protect the gasoline reservoir.

These together with certain other novel features of construction and arrangements of the parts more fully hereinafter described constitute my invention.

Referring to the drawings: Figure 1. is a plan view of my improved fire engine; Fig. 2. is a side elevation of the same; Fig. 3. is a view of the rear end of the fire engine; and, Fig. 4. is a vertical section on line 4-4 Fig. 2.

In the drawings 1 is the front axle and 2 is the rear axle, on which are mounted the wheels 3 and 4. Extending between the front and rear axles and supported thereby are the two main beams 5 and 6, preferably of channel iron, as shown in cross-section, Fig. 4; between the main beams 5 and 6 are cross-pieces 7 which are bolted between the main beams and form a rigid frame for supporting the engines and pumps.

The main beams 5 and 6 are provided with upwardly curved portions 9 to allow the front wheels of the fire engine to pass under them

when the forward truck carrying the front wheels is turned.

The engine consists of a plurality of cylinders 10, in the drawings I have shown six 60 cylinders in which an explosion takes place at both ends of the cylinders. The engine frame 12 rests upon the main beams 5 and 6 and carries the main driving-shaft 15 of the engine, which extends lengthwise of the 65 frame. By so constructing the frame the engine and pumps are supported in such a manner that endwise oscillations are avoided and by having the driving-shaft extending lengthwise of the frame any number of cylinders 70 may be added to the engine.

In the drawings I have shown rotary pumps but any other type may be used. The said pumps 16 and 18 are mounted on the pump base or housing 20, which is supported on the main beams 5 and 6. Each 75 of the pumps is provided with two pump shafts 21 and 22, coupled together by gear-wheels 23 and 24 at one end and at the other end by gear-wheels 25 and 26, thus insuring 80 a uniform motion to both shafts.

The main driving-shaft 15 of the engine is provided with gear-wheels 28 and 30, the former 28, meshing with a gear-wheel 29 on the pump shaft 22, of the pump 18, and the latter, 30, meshing with a gear-wheel 31, on the pump shaft 22 of the pump 16.

The water inlet pipe 40 for the pumps is shown in Figs. 2 and 4, this communicates with both pumps. Valves 41 and 42 are 90 provided so that the supply of water to either may be cut off.

Each pump is provided with separate discharge outlets 34 and 36. Between the pumps 16 and 18 is a connecting-pipe 38, 95 provided with a valve 39, by means of which the water from one pump may be discharged through the outlet of the other pump, and the water from both pumps may then be forced out of the discharge outlet of one pump. The hose may be coupled to the outlet of both of the pumps, and when the valve 39 is open it will equalize the pressure of the water. When a high pressure of water is desired the valves 39 and 41 are closed 100 and the valve 35 opened so that the water will flow from the pump 18, through the pipe 37, to the inlet of pump 16. The pressure of the water will then be again raised by the action of the pump 16, above the pressure 105 exerted by the pump 18.

The water-jackets of the cylinders 10 of

the engine are supplied with water from the water tank 44, which may be filled through the pipe 45 from the pumps. The water circulates through the pipes 46 and 47, by means of the pump 48, driven from the main driving-shaft 15 and the water returns from the water-jackets, through the pipe 49, to the water tank 44.

A compressed air tank 50, connected with the cylinders 10, by a pipe 60, is provided for the purpose of starting the engine. An air pump 51, driven from the main driving-shaft 15, forces air into the air tank 50.

At the forward end of the frame 5 and 6 is located the gasolene tank 52, which is incased in an outer casing 53. The space between the tank 52 and the outer casing 53 is supplied with water, through the pipe 54 from the pumps. An overflow pipe 55, is provided so that the water will circulate and keep the oil tank 52 cool, when the fire engine is in close proximity to a fire.

The gasolene is carried from the tank 52 through the pipe 56 to the carburetor 57, from which it is drawn into the cylinders, through the pipe 58, in the usual manner.

By the arrangement of the direct gearing between the main driving-shaft of the engine and the pumps, the necessity of interposing a clutch between the engine and the pumps is avoided, thus the construction is simplified.

Either double or single acting engines may be used without departing from my invention and in place of having the two pumps arranged side by side they may be placed in line and mounted on the same pump shafts. The pumps may be either the rotary or centrifugal type without departing from my invention.

Having thus described my invention I claim and desire to secure by Letters Patent:

1. In a fire engine the combination of a frame, an engine on said frame, a pump on said frame driven by said engine, a gasolene tank on said frame, a casing inclosing said gasolene tank to form a water jacket around said first mentioned tank, a pipe connecting said gasolene tank with said engine, and an over-flow pipe from said outer casing surrounding the said gasolene tank.

2. In a fire engine the combination of a frame having main beams extending longitudinally, wheels supporting said frame, an

internal combustion engine having a plurality of cylinders, said frame extending under said engine and supporting the same, a plurality of pumps mounted on top of said frame at the end of said engine, gear-wheels between said pumps and the driving-shaft of said engine, said pumps having separate discharge outlets, a pipe connecting the discharge outlet of one of said pumps with the inlet of the other one of said pumps, a valve in said last mentioned pipe, and an inlet pipe to supply water to said pumps.

3. In a fire engine the combination of a frame having main beams extending longitudinally, wheels supporting said frame, an internal combustion engine having a plurality of cylinders, said frame extending under said engine and supporting the same, a plurality of pumps mounted on top of said frame at the end of said engine, a driving-shaft in said engine, a pump shaft in each of said pumps, a gear-wheel on each of said pump shafts meshing with gear-wheels on the said driving-shaft of said engine, said pumps having separate discharge outlets, a pipe connecting the discharge outlet of one of said pumps with the inlet of the other one of said pumps, a valve in said last mentioned pipe and an inlet pipe to supply water to said pumps.

4. In a fire engine the combination of a frame having main beams extending longitudinally, wheels supporting said frame, an internal combustion engine having a plurality of cylinders, said frame extending under said engine and supporting the same, a plurality of pumps mounted on top of said frame at the end of said engine, gear-wheels between said pumps and the driving-shaft of said engine, said pumps having separate discharge outlets, a pipe connecting the discharge outlet of one of said pumps with the inlet of the other one of said pumps, a valve in said last mentioned pipe, an inlet pipe to supply water to said pumps, separate connecting pipes between said inlet pipe and each of said pumps and valves arranged in said last mentioned connecting pipes.

In testimony whereof I affix my signature in presence of two witnesses.

WILLIAM FRANCIS GIBBS.
